UNITED STATES PATENT OFFICE.

GEORGE MULLER, OF NEWARK, NEW JERSEY, ASSIGNOR TO LEO SCHLESINGER, OF NEW YORK, N. Y.

TOY GUN.

1,186,120.

Specification of Letters Patent.

Patented June 6, 1916.

Application filed March 20, 1915. Serial No. 15,847.

To all whom it may concern:

Be it known that I, GEORGE MULLER, a citizen of the United States, and a resident of Newark, in the county of Essex and State of New Jersey, have invented certain new and useful Improvements in Toy Guns, of which the following is a specification.

The present invention relates to toy guns and more particularly to that class of toy guns in which a piece of paper is broken by the compression of air in a cylinder caused by a movable piston, so that the sudden breaking of the paper produces a report.

15 The object of my invention is to provide a device of this character which will form an efficient compression of the air in the cylinder and which will produce a very loud report when the paper is broken.

20 Another object of the invention is to produce a toy gun which will be very easy to operate and one which will be durable.

Another object of the invention is to provide a gun which may be very quickly operated.

Another object is to provide a gun which may be inexpensively stamped from sheet metal and which can be assembled with the least possible soldering.

25 In the drawings forming part of this application, Figure 1 is an elevation of a toy gun embodying my invention, Fig. 2 is an elevation of one end thereof, showing the paper clamped tightly, preparatory to firing, Fig. 3 is a similar view looking at the opposite side of the gun, Fig. 4 is a longitudinal sectional view, taken on the line 4-4 of Fig. 1. Fig. 5 is a plan view, and; Fig. 6 is a sectional view, taken on the line 40 6-6 of Fig. 4.

The device consists, primarily, of a cylinder 1 which is preferably made from sheet metal. The seam shown in the drawings is preferred as it prevents escape of the air and the interior bore of the cylinder may be made very symmetrical. This seam, as shown in Fig. 6, is made by turning back the edges 2 of the cylinder and by arranging a separate strip 3 having inturned edges 4 over the edges 2 and by pressing the parts together. There is a piston sliding in this cylinder, which may be of any desired construction but which is here shown as consisting of a rod 5 which extends through an aperture in a cap 6 fixed on the end of the

cylinder, and which rod has a handle portion 7 outside the cylinder; of the flanges 8 carried by the rod, and of a washer or packing 9 held between the flanges and in close fit with the bore of the cylinder. The piston is adapted to compress the air in its upward movement.

In order to form a more airtight seat for the paper there is provided an annular member 10 which is soldered to the top of the cylinder. This member has a turned down and rounded portion 11 which forms a seat for the piece of paper 12, and there is an aperture 13 to permit the compressed air of the cylinder to pass through and act on the paper.

There is a sleeve member 14 which is revoluble and slidable on the cylinder, and it has a projecting lip 15 which serves as a finger piece for turning and sliding the sleeve. Preferably, this sleeve does not extend entirely around the cylinder so that its edges 16, 17 may strike against the seam 3 of the cylinder to limit the turning movement of the sleeve in either direction. Projecting from the sleeve are the arms 18 which preferably turn out at 19 and then upward at 20 to provide ample space for the insertion of the paper; and the upper ends of the arms are secured to an annular cup 21 by means of lugs 22 stamped from the edge of the cup and passing through the arms and turned over, as shown.

There is preferably an amplifier or horn member 23, which is secured to the cup 21 by turning its edge over the edge of the cup as shown at 24. The cup 21 forms a socket for a packing 25 which preferably consists of a washer of rubber or other resilient material.

In order to force the parts tightly against the paper there is provided means for moving the cup 21 downwardly, simultaneously with the turning of the sleeve. For this purpose there is a ring 26 around the upper end of the cylinder. This ring may be loose on the cylinder, thus avoiding additional soldering, and it may be prevented moving upwardly by the flange 27 on the top member 10 and it may be prevented from revolving by the engagement of its ends 28 against the projecting seam 3 of the cylinder. This ring has cam projections 29 preferably at opposite sides of the gun, as shown in Figs. 2 and 3. These projections engage, respec-

tively, in a slanting recess 30 in the sleeve 14 and with the edge 17 thereof.

Operation: In order to use the device the cylinder is held in one hand, with the sleeve 5 and cup 21 in raised position and a piece of paper is inserted between the member 10 and the washer 25 so as to lie on the former and cover the aperture therein. The washer is then forced downwardly to make an air-tight connection between the paper and the member 10, so that the air compressed by the piston cannot escape except by breaking the paper. This lowering is accomplished by pressing the finger piece 15 to turn the sleeve to the right in Fig. 1. As the sleeve is thus turned the projections 29 on the ring 26 force the sleeve downwardly and since the cup 21 and washer 25 are carried with the sleeve the washer is compressed upon the paper and upon the member 10 and the connection between the paper and the member 10 is completely sealed. The washer 25 is more or less compressed to hold the paper tightly and well sealed, regardless of any slight imperfection in the top surface of the member 10. The piston, having been drawn outwardly, is quickly forced inwardly toward the top of the cylinder, and when the compression of the air in the cylinder is sufficient to overcome the strength of the paper the latter is broken and a loud report is made thereby. The sound made by the

breaking of the paper passes through the washer 25, and through the member 23, being more or less amplified or directed by the latter. To again use the device it is only necessary to press the finger piece 15 to the left and possibly press it upwardly to raise the sleeve and the parts connected therewith sufficiently to remove the pressure of the washer from the paper. The paper may then be advanced to bring an unbroken portion across the member 10 and the previous operations are repeated.

Having described my invention, what I claim is:

A device of the class described, comprising a cylinder having a projecting seam, a piston, an annular member forming a seat, and secured to one end of the cylinder, a ring on said cylinder abutting on said seat member to prevent it sliding on the cylinder and having its end abutting the seam of the cylinder to prevent its turning, cam portions on said ring, a sleeve revoluble on the cylinder and engaging the cam portions of the ring whereby the ring will force the sleeve along the cylinder when the sleeve is turned and an annular member carried by said sleeve and coöperating to clamp a piece of paper on said seat member.

Signed at the city, county and State of New York, this 17th day of March, 1915.

GEORGE MULLER.
